UNITED STATES PATENT OFFICE

CHESTER M. POETSCH, OF CHICAGO, ILLINOIS

GAME SCORING DEVICE

Application filed October 11, 1930. Serial No. 487,952.

This invention relates to a game scoring device; and more particularly to a device arranged for conveniently and quickly keeping score in a game which is played with an instrument having a rod-like part or shaft, like a golf club.

One of the main objects of this invention is to provide a scoring device which is arranged to be mounted on the shaft of an instrument with which the game is being played, and in such a position, so that the score can be conveniently recorded thereby and may be readily observed.

Another object is to provide such a scoring device which is arranged to be readily mounted on the shaft of the instrument used, like a golf club, without marring or modifying the construction of said shaft or any part of the instrument, and so that the device can also be readily detached therefrom when it is not desired.

A further object is to provide such a device whereby a score card is carried in a handy position so that the scores can be readily marked thereon, and so that said card can also be readily removed and replaced by a new one.

A still further object is to provide a score card having notches in its marginal portion, to aid in readily mounting and retaining the card in position on suitable supporting means therefor.

These and other objects and advantages are attained with this invention, as will become apparent from the following description, taken in connection with the accompanying drawing, in which,—

Fig. 1 is a view of a golf club having my invention mounted in position on the shaft thereof.

Fig. 2 is a plan view of my scoring device, mounted on a shaft portion of a golf club.

Fig. 3 is a longitudinal sectional view through the device, taken on line 3—3 of Fig. 2.

Fig. 4 is an inverted plan view of the scoring device.

Figs. 5 and 6 are vertical cross-sectional views, taken respectively through lines 5—5 and 6—6 of Fig. 3.

Fig. 7 is a broken view of the form of score card arranged for use with my invention.

The present invention is particularly adapted and arranged for attachment to the shaft or rod-like part of an instrument with which the game is played, like the shaft 8 of a golf club 9, and it is positioned so that it is always ready at hand to have the scores quickly and conveniently marked or recorded thereon.

The accompanying drawing illustrates my game scoring device in a certain form of construction, and this form comprises a frame 10, having a table-like top portion or supporting portion 11, for supporting a score-receiving member, as a score card 12 thereon. Lugs or holding fingers 13 are extended upwards from the ends of the frame and have their ends 13' extending inwardly over said top portion 11; while the scoring member or card 12 is preferably provided with notches 14, in the marginal portion, as best shown in Fig. 7, therewith providing extending portions 15, at the sides of said notches, so that these portions 15 embrace the lug 13, and the lug ends 13' overlap the card, whereby the card is held securely in position but permits convenient removal thereof for replacing it by a new card. Suitable legend 16 is provided on said card, to adapt it for readily keeping the score during the golf game.

The frame 10 is provided with means for mounting it on the instrument which is used in playing the game, as on the shaft 8, of the golf club, and preferably on the side opposite the head 17; so that when the weight of the head swings it downwards while the club is being held in the hand, this scoring device will be automatically positioned on the upward side, as indicated in Fig. 1 of the drawing, and it is thus conveniently at hand so that the score can be readily entered or recorded thereon and may also be readily observed. Said mounting means comprises a pair of bands or clamping members 18, which are arranged to embrace the shaft 8, the two end portions 19 of each band being preferably overlapped, as shown. A screw 20 extends through the top portion 11, continues through an opening or seat 21 provided be-

tween an end shoulder 22, and an intermediate shoulder 23, and a pair of lips or flanges 24 which connect said shoulders, all depending from said top portion 11; and said screw 5 further extends through holes provided in the joining pair of said end portions 19, and engages in a nut 25 positioned below said end portions.

By tightening the pair of screws 20, the 10 bands 18 will be drawn tightly upon the shaft 8, and press said shaft firmly against the bottom parts of shoulders 22 and 23, thereby securely and positively holding this device in the desired position on the shaft.

15 The elements or means for recording or marking the score on the score card, in the present form of my invention, comprises a marking element 27, which is shown in the form of a pencil herein, and may be in any 20 suitable form for writing or properly marking the scores on the cards.

Means is provided for mounting and retaining the pencil or marking element 27 on the device, so that it will always be ready at hand, and this means preferably comprises a cord or flexible means 28, which is secured at one end to the pencil, as by means of a split ring 29, which is set into a peripheral groove on said pencil, to provide a smooth 30 exterior for the pencil. The other end of said cord is secured to a roller or drum 30, preferably of fibre, which is mounted on a shaft 31, so that it can slide and rotate thereon.

35 The shaft and the roller thereon are mounted in a housing 32, provided between the shoulders 23, and flanges 33 which depend from the top portion 11 and in line with flanges 24. Said shaft 31 has its ends set in notches provided in said shoulders 23, and 40 is held in place by suitable plugs 34, which are forced in said notches beneath said ends. A coil spring 35 is mounted on said shaft and has one end attached to said roller 30, and its other end is suitably held or braced, so 45 that the spring will automatically wind the cord on the roller and will draw the pencil into one of the dished or curved parts 36, which are provided at the outer sides of flanges 33, and closely beneath the top portion 11 of the device. Slots 37 are preferably 50 provided in each flange 33, for the cord to pass through in order to properly seat the pencil in either one of the seats or dished parts 36.

55 The device is mounted in position on the golf club, so that when said club is supported in the hand and the head 17, by its weight, moves downwardly, this device will be positioned upwards and conveniently for marking the scores on the score card. The pencil is also positioned so as to be ready at hand, and to be conveniently drawn outwardly 60 from the device for marking the score on the score card, thereby tensioning the spring 65 so that the latter will automatically draw

the cord on the roller and the pencil back in position when the pencil is released. The score card is also handily positioned on the top part 11, and can be readily flexed and removed therefrom and a new one substituted 70 therefor, the notches at its ends adapting it particularly for this form of my invention.

I claim as my invention:

1. A golf scoring device comprising frame means provided with means for detachably carrying a score card thereon, depending flange means on said frame means and band means co-operating therewith for clasping a golf club therebetween, and adjusting means for tightening said band means and thereby 75 clamping the latter and the flange means upon said club, so that this device will be held in position for readily keeping score and can be readily detached from the club without marring the same. 80

85 2. A game scoring device comprising frame means arranged for detachably carrying a score card thereon, means on said frame means including spaced flanges providing seating means on the outside thereof for receiving a scoring element and means mounted between said flanges and connected with said element so that said element may be drawn from the device for use and when released will be automatically returned and seated in 90 said seating means and carried thereby. 95

100 3. A game scoring device comprising a card-supporting portion and means for removably retaining the score card thereon, a seating portion for receiving a score marking element to hold it out of the way and concealed by said supporting portion, and means attached to said element and to the device to permit withdrawing the element 105 for marking the score on said card and whereby said element is again automatically returned and seated in said seating portion upon release of the element. 110

115 4. A game scoring device comprising a frame having a table portion, means for retaining a score card on said table portion so that it may be readily removed therefrom and replaced, said frame having a dished portion providing a seat for seating a marking element therein, and means, including flexible 120 means extendible from said frame, to be connected with a marking element, whereby to enable drawing said element outwards for marking the score card and for automatically returning said element in said seat. 125

130 5. A game scoring device comprising a frame having a table portion and means for retaining a score card thereon so that it may be readily removed therefrom and replaced, said frame having a dished portion providing a seat for receiving a marking element, a housing portion provided in said frame, a coil spring and a roller secured thereto and suitably mounted in said housing portion, and flexible means secured, adapted to be con-

4 nected with said roller and to said marking
element, to enable convenient use of said
element for marking the score on said card
and whereby said element is automatically
returnable to said seat.

5 6. A game scoring device comprising a
frame having a card supporting portion and
means thereon for removably retaining a
score card thereon, members depending from
10 said supporting portion and providing a seat-
ing portion for receiving a score marking
element, means housed between said depend-
ing members and having means attachable to
15 said element, so that the element may be
drawn from the frame for use and will be
automatically returned to said seating portion
when released, and means cooperating
20 with part of said depending members for
detachably securing the device on the ex-
terior of the shaft part of the instrument
wherewith the game is being played, so that
the score may be readily marked on said card
25 and may be readily observed.

7. A golf scoring device comprising frame
25 means having a supporting portion for car-
rying score receiving means thereon, means on
said frame means for carrying marking means
to mark the score on said receiving means,
means including integral spaced flanges
30 depending from said supporting portion also
cooperating band means, for clasping a golf
club, and adjustable means for tightening
said band means on said club and drawing
35 said club against the flanges, so as to hold
it firmly but detachably thereon and with-
out marring the club.

In testimony whereof I have signed this
specification.

CHESTER M. POETSCH.
